UNITED STATES PATENT OFFICE.

EDWARD F. BAKER, OF CHICAGO, ILLINOIS.

PACKAGE OF FLY-PAPER.

SPECIFICATION forming part of Letters Patent No. 400,035, dated March 26, 1889.

Application filed January 24, 1888. Serial No. 261,791. (No specimens.)

To all whom it may concern:

Be it known that I, EDWARD F. BAKER, of Chicago, county of Cook, and State of Illinois, have invented certain new and useful Improvements in Packages of Fly-Paper, of which the following is a full, clear, and exact description, which will enable others to make and use the same, reference being had to the accompanying drawings, forming a part of 50 this specification.

The object of this invention is to provide a means or device for compressing or binding together the several sheets composing a package of fly-paper, so as to prevent the composition 55 spread over the surface from being expressed between the edges and the merchantable quality of the goods destroyed.

Figure 1 is a plan or face view of a sheet of fly-paper; and Fig. 2, a package of the same, which embodies my improvement. Fig. 3 is a view of the binding-clamp.

In the drawings, A represents a sheet of fly-paper, the dark or shaded surface *a* representing the sticky coating or composition applied 25 to the same.

In preparing the fly-paper the mixture is applied to one side of the sheet only, and is spread over so as to leave the clean marginal space *a'* between the border of the composition 30 and the edge of the paper, as shown in Fig. 1. After the sticky composition has been applied the sheet is folded over upon itself along the line *b* with the sticky surface inside.

In packing the paper for storage or shipment a number of sheets are laid one on top of the other, to form a package, B, such as is shown in Fig. 2. These packages are of a convenient size for the retail trade, and a number of them are usually placed in the same 40 box or shipping-case.

Under ordinary circumstances it was found that the composition would be expressed or ooze out between the edges and cause the different sheets to adhere or stick together, thus 45 damaging the goods and resulting in a com-

plete loss to the producer. The principal object of this improvement is therefore to prevent this class of goods from being damaged in the manner set forth. This I accomplish by the use of the spring-clamp C, which is of 50 the form shown in Fig. 3. This clamping device is composed of a single piece of spring-wire, and consists of the double end bars, *d d'*, and the double side bars, *d² d²*, running at right angles to the end bars.

The clamp or binder C is applied to the package in the manner shown in Fig. 2, the respective parallel bars coming opposite each other on opposite sides of the package, the line of pressure being confined to a point between the border of the composition and the edge of the paper, thus preventing the coating from oozing out or being expressed between the open edges. The clamp has a bearing along the ends and front sides, the backs 60 formed in folding the leaves resting against the bent-around parts *d³ d³* of the clamp, as shown in Fig. 2.

The terminal ends of the wire composing the clamp may lap past each other and be 65 wired together, as shown, or secured in any other suitable manner.

Having thus described my invention, what I claim as new, and desire to secure by Letters Patent, is—

The combination, with a package of fly-paper, of a spring-clamp consisting of the double end bars, *d d' d' d'*, and the side bars, *d² d²*, running at right angles thereto, the end bars being bent to pass around the back of the 80 package, whereby the same is compressed from both sides on a line between the border of the composition and the edge of the paper, the terminal ends of said spring overlapping and being wired together, as shown, all substantially as and for the purpose set forth.

EDWARD F. BAKER.
